UNITED STATES PATENT OFFICE.

WILLIAM BENGEL, OF NEWPORT, ARKANSAS.

JACK.

Application filed October 7, 1922. Serial No. 592,954.

To all whom it may concern:

Be it known that I, WILLIAM BENGEL, a citizen of the United States, and a resident of Newport, in the county of Jackson and State of Arkansas, have invented certain new and useful Improvements in Jacks, of which the following is a specification.

My present invention relates generally to lifting devices, and more particularly to automobile jacks, my object being the provision of a strong, durable and effective device of this nature which will admit of the engagement of the part or parts to be raised at a point close to the ground on which the jack rests, and thus capable of effective use where the ordinary jack cannot be employed.

In my improved jack a lever having means at one end to directly engage the part or parts to be lifted, works up and down upon an upright extending vertically from a ground engaging supporting plate, by virtue of opposing spring controlled dogs which engage oppositely disposed ratchet faces of the upright. At the opposite end of the lever is a handle and in addition to its other parts the lever carries a dog releasing member and an actuating and controlling element for the dog releasing member whereby the dogs may be forced and held out of engagement with the ratchets of the upright in order to permit of lowering movement of the lifting lever. My invention also contemplates the provision of a lever the dogs of which are so formed as to bring about binding engagement between the same and the upright when the lever lowers under a weight supported thereby, capable of manual release upon downward pressure upon the handle end of the lever.

In the accompanying drawings which illustrate my present invention and form a part of this specification,

Figure 1 is a perspective view of my improved jack with the handle removed,

Figure 2 is a detail perspective view of the handle,

Figure 3 is a detail perspective view of one of the dogs,

Figure 4 is a fragmentary side view of a portion of the upright and the lever, the latter partly broken away and in section,

Figure 5 is a detail perspective view of the dog releasing wedge and portions of the dogs engaged by the wedge, and

Figure 6 is a perspective view of a portion of the lifting lever with the dogs removed.

Referring now to these figures and particularly to Figure 1, my invention contemplates a rectangular upright 10 rising from any suitable form of flat base 11 adapted to rest upon the ground or similar support, the opposite edges of which upright are provided with ratchet teeth 12, and the opposite sides of which upright have central longitudinal grooves 13.

The lifting lever proposed by my invention is preferably of elongated form rectangular in cross section as indicated at 14, having at one end a reduced polygonal extension 15, the latter adapted to receive thereover the end socket 16 of a handle 17. The opposite end of this lever has a claw shaped extension 18 for direct engagement with the work to be lifted, and its body is provided with a longitudinal slot 19 through which the upright 10 extends, and has opposing inwardly projecting lugs 20 centrally of the opposite sides of its slot 19 which extend into the side grooves 13 of the upright and thus position the latter centrally of the slot 19 of the lever, these lugs being rounded so that the lever can be rocked up and down on the upright.

Within opposite ends of the slot 19 of the lifting lever 14, a pair of lifting dogs 21 are pivoted upon transverse pivot bolts 22, these dogs having reduced engaging extensions 23 projecting below the lever and normally held in engagement at their lower free ends with the ratchet edges 12 of the upright 10 by virtue of springs 24 whose lower inner free ends engage the lower portions of the dogs and whose upper outer ends are fixed to the body of the lifting lug by screws or like anchoring members 25, adjacent to opposite ends of the lever slot 19.

With the parts as thus far described it is obvious that upon association of the handle 17 with the handle receiving end of the lever 14, the latter may be oscillated vertically and will mount the upright 10 so that during such oscillation the latter will force vertically shifting movement of the lever.

In releasing the lifting lever for downward movement on the upright it is obvious some means must be provided for disengaging the dogs 23 from the upright ratchets. To do this I provide a vertically shiftable dog releasing member whose lower portion is in the nature of a dog engaging spreader 26 and whose upper reduced shank 27 is slideable along one side of the body of the lift-

ing lever and has a laterally outstanding pin 28 projecting through the arcuate slot 29 of a control lever 30 fulcrumed upon a pivot bolt 31 laterally outstanding from one side of the body of the lifting lever and having at its opposite end a handle 32. Thus the lower wedge shaped head 26 of this releasing member is, upon downward movement of the member forced to spread the lower portions of the dogs 21 apart. This wedging head engages the dogs by virtue of laterally outstanding angular extensions 33 at the lower ends of the dogs, and is held centralized between the dogs at all times by virtue of its inwardly projecting vertical rib 34 which extends into and is movable within one of the side grooves 13 of the upright 10.

It will be observed that the upper portions of the dogs 21 inwardly beyond their pivots 22, have convexly rounded upright engaging surfaces so disposed as to come into action when, after downward movement of the dog releasing member, the lifting lever 25 lowers on the upright under a weight as for instance the work upon its work engaging end 18. It is obvious that under such circumstances the work engaging end will be depressed below the handle end of the lever and thus the rounded upper inner portions 30 of the dogs will come into binding engagement with the ratchet edges of the lever so as to act as a check against too rapid lowering movement, which binding engagement 35 may be released in whole or in part by manual pressure of the operator downwardly upon the handle end of the lever.

It is also obvious that by virtue of this construction and arrangement of parts the lifting lever including its work engaging end, may be lowered to and against the flat supporting base 11 and may engage work at a level but slightly above that of the supporting surface on which the jack as a whole rests. By the use of an elongated handle 17 and by virtue of the close proximity of the work engaging end of the lever to the upright, considerable leverage may be exerted in the lifting of the work, and it is 40 equally obvious that instantaneous release 45 may be effected when it is desired to permit the work to be again lowered.

I claim:

1. A jack including an upright having a

supporting base and opposite ratchet faces, 55 a lever slidably guided on the upright and oscillatable with respect thereto, said lever being directly engageable with the work at one end and having an opposite handle end, 60 spring controlled dogs pivotally supported by the lever and having depending portions engaging the ratchet faces of the upright, and a member carried by and shiftable with the lever and movable between and in engagement with the engaging portions of 65 said dogs to force the latter out of engagement with the ratchet faces of the said upright.

2. A jack including an upright having a supporting base and opposite ratchet faces, 70 a lever slidably guided on the upright and oscillatable with respect thereto, said lever being directly engageable with the work at one end and having an opposite handle end, 75 spring controlled dogs pivotally supported by the lever and having depending portions engaging the ratchet faces of the upright, and a member carried by and shiftable with the lever and movable between and in engagement with the engaging portions of said 80 dogs to force the latter out of engagement with the ratchet faces of the said upright, said dogs having upper inner convexly rounded surfaces opposite their pivots, normally spaced from the adjacent faces of the 85 upright and movable into binding engagement with the latter upon tilting of the lever with respect to the upright.

3. A jack including an upright having a supporting base and opposite ratchet faces, a 90 lever slidably guided on the upright and oscillatable with respect thereto, said lever being directly engageable with the work at one end and having an opposite handle end, and opposing spring controlled dogs carried 95 by the lever and engaging the opposite ratchet faces of the upright, said dogs having laterally projecting angular extensions at their lower engaging ends, a wedge member vertically shiftable at one side of the 100 lever engageable with the said extensions of the dogs to force the latter out of engagement with the ratchet faces of the upright, and a controlling and actuating lever for the said wedge fulcrumed upon the adjacent 105 side of the lifting lever and operatively connected to the wedge as described.

WILLIAM BENGEL
